[57] CLAIM

I claim the ornamental design for an extruded post, as shown and described.

DESCRIPTION

FIG. 1 is a front elevational view;
FIG. 2 is an exploded view thereof;
FIG. 3 is an enlarged fragmentary side elevational view of a second embodiment illustrating the groove only that is adaptable to the post of the first embodiment; and,
FIG. 4 is an enlarged fragmentary side elevational view of a third embodiment illustrating the groove only that is adaptable to the post first embodiment.
